[57] CLAIM

The ornamental design for a writing instrument, as shown and described.

DESCRIPTION

FIG. 1 is a front elevational view of a writing instrument showing my new design, with the cap member in a stored position;

FIG. 2 is a front elevational view with the cap member removed for convenience of illustration;

FIG. 3 is a rear elevational view of FIG. 2;

FIG. 4 is a right side elevational view of FIG. 1;

FIG. 5 is a bottom plan view of FIG. 1;

FIG. 6 is a bottom plan view of FIG. 2;

FIG. 7 is a top plan view of FIG. 1;

FIG. 8 is a top plan view of FIG. 2;

FIG. 9 is a left side elevational view with the cap member in a closed position;

FIG. 10 is a front elevational view of FIG. 9;

FIG. 11 is a rear elevational view of FIG. 9;

FIG. 12 is a bottom plan view of FIG. 9; and,

FIG. 13 is a top front view similar to FIG. 9.
